UNITED STATES PATENT OFFICE.

CHARLES L. DEPOLIER, OF NEW YORK, N. Y., ASSIGNOR TO DUBOIS WATCH CASE COMPANY, OF BROOKLYN, NEW YORK, A CORPORATION OF NEW YORK.

CHATELAINE BROOCH-WATCH.

No. 890,501.

Specification of Letters Patent.

Patented June 9, 1908.

Application filed January 3, 1908. Serial No. 409,196.

To all whom it may concern:

Be it known that I, CHARLES L. DEPOLIER, a citizen of the United States, residing in New York, in the borough of Brooklyn, 5 county of Kings, and State of New York, have invented certain new and useful Improvements in Chatelaine Brooch-Watches, of which the following is a specification.

This invention relates to a combination of 10 lady's watch and chatelaine to which I have given the name of "chatelaine - brooch - watch", and by which a separate chatelaine-brooch and bow for watches that are suspended from the waists are dispensed with, 15 and a very ornamental and attractive lady's watch for direct suspension from the garment supplied; and for this purpose the invention consists of a watch-case provided with a chatelaine-brooch which is hinged to 20 the watch-case at both sides of the pendant, said brooch being composed of two portions,—a lower one hinged to the case and an upper one swiveled to the hinged portion, the swiveled portion being provided with means 25 for attaching the watch to the garment, and with an eye for permitting it to be used with a chain.

The invention consists further of certain 30 details of construction which will be fully described hereinafter and finally pointed out in the claims.

In the accompanying drawings, Figure 1 represents a front-elevation of my improved 35 chatelaine-brooch-watch, Fig. 2 is a rear-view, Fig. 3 is a side-view, and Figs. 4, 5 and 6 are respectively a front-view, a rear-view and a side-view of a modified construction of the chatelaine-brooch-watch.

Similar letters of reference indicate corresponding parts throughout the several views.

Referring to the drawings, *a* represents a 40 watch-case of any approved construction. To the watch-case are applied at both sides of the pendant *p* hinge-joints formed of perforated ears *e* to which is hinged a chatelaine-brooch which is composed of two parts,—a lower hinged part *b* and an upper portion *b*¹ which is swiveled to the lower part and provided at its rear with means for attaching it 45 to the garment. These means consist of a pin-tongue *d* which is hinged at *d*¹ to one side of the swiveled portion *b*¹ and a stationary receiving-catch *d*² which is attached to the opposite side of the swiveled portion *b*¹, as 50 shown clearly in Fig. 2. To the upper end of

the swivel-pin *f* by which the hinged and swiveled portions *b* *b*¹ of the chatelaine brooch *b* are connected is applied an eye *f*¹ which is hinged thereto so as to be folded down over the swiveled portion of the chatelaine-brooch or held in upright position thereon for attaching it to a chain in case the watch is to be carried on a chain instead of being applied to the waist or other garment.

The chatelaine - brooch - watch just described can be directly attached to the garment without requiring a separate chatelaine-brooch or bow. It can be readily turned up on the hinged portion of the chatelaine-brooch so as to conveniently read off 65 the time when hung on the garment. The chatelaine-brooch can also be used with watches which have no pendant and stem, such as are wound up by a key or other arrangement from the inside, the chatelaine-brooch dispensing with both the brooch and bow.

In place of making the pin-tongue and catch for the watch stationary on the chatelaine-brooch, the pin-tongue *d* may be attached to a separate bar *g* which is swiveled to the center of the hinged portion of the chatelaine-brooch, as shown in Figs. 4-6, and which is provided at one end with a hinge-joint *g*¹ for the pin-tongue and at the 70 other end with a stationary catch *g*² for locking the pin-tongue, the bar *g* being also provided with a hinged eye *g*³ for using the watch with a chain in case the watch is not to be suspended from the garment. The eye 75 *g*³ can be bent over the end of the pin-tongue adjacent to the catch so as to abut against said catch, as shown in dotted lines in Fig. 6, in which position it forms a safety-device for the pin-tongue so as to prevent its unlocking 80 from the catch. When the chatelaine-watch is to be used with a chain, the pin-tongue with its swiveled supporting-bar is moved into vertical position in line with the center of the chatelaine-brooch, and the eye placed 85 in line with the same for receiving the chain; while when it is applied to the garment, the pin-tongue is placed in position across the chatelaine-brooch, the watch being then suspended vertically below the swivel-connection 90 with the chatelaine-brooch.

The novel features of the improved chatelaine-brooch-watch are the direct and non-detachable suspension of the same from the 95 garment of the wearer, the use of the chate-

laine-brooch-watch with a suspension chain, and the use of the hinged suspension-eye as a safety-device for the pin-tongue when the watch is applied to the garment.

5 Having thus described my invention, I claim as new and desire to secure by Letters Patent:

10 1. The combination, with a watch - case provided with ears, of a chatelaine-brooch hinged to the same and provided with means swiveled to the hinged portion of the chatelaine-brooch for attaching it directly to the garment.

15 2. The combination, with a watch - case provided with ears, one at each side of the pendant, of a chatelaine-brooch composed of a lower hinged portion and an upper swiveled portion, the swiveled portion being provided with means for attaching it to the garment.

20 3. The combination, with a watch-case of

a chatelaine-brooch hinged thereto and provided with swiveled fastening device for attaching the chatelaine-brooch directly to the garment, and with an eye hinged to said swiveled device for suspending the chatelaine from a chain. 25

4. The combination, with a watch-case of a chatelaine-brooch formed of a lower portion hinged to the watch-case and an upper swiveled portion provided with a hinged pin-tongue at one side and a catch at the other side and with a hinged eye on the swiveled portion. 30

35 In testimony, that I claim the foregoing as my invention, I have signed my name in presence of two subscribing witnesses.

CHARLES L. DEPOLIER.
